WIRE CUTTING MACHINE

Fredric C. Muntwyler, Oak Park, Ill., assignor to
Wire Sales Company, Chicago, Ill., a corpora-
tion of Illinois

Application January 15, 1940, Serial No. 313,855

7 Claims. (Cl. 140—146)

The machine of the present invention is de-
signed for the purpose of severing uniform sec-
tions from a continuously fed wire and is pro-
vided with means for regulating the length of the
sections so cut.

5 The object of the invention is to increase the
speed of the cutting operation by feeding the
wire continuously rather than intermittently in
the manner commonly employed in the severing
of wire sections.

10 The above results are obtained by employing a
movable wire guide which at uniform intervals
flexes the advancing wire laterally into the path
of the cutters and to the means provided for
15 timing such flexions in ratio to the feeding speed
of the wire, so that each cut will sever a section
of uniform length depending upon the coor-
dinated adjustment of the various portions of the
machine.

20 Further objects and details will appear from
the description of the invention in conjunction
with the accompanying drawings, wherein—

Figure 1 is a side elevation of the machine as a
whole;

25 Fig. 2 is a top plan view of the machine show-
ing portions of the casing removed;

Fig. 3 is an enlarged cross sectional elevation
taken on line 3—3 of Fig. 2 showing the gear
train and cam for actuating the oscillating wire
30 guide;

Fig. 4 is a longitudinal sectional elevation taken
on line 4—4 of Fig. 3 showing the wire guide and
cutters;

Fig. 5 is a sectional plan view of the same parts
35 taken on line 5—5 of Fig. 4;

Fig. 6 is a sectional elevation taken on line
6—6 of Fig. 2;

Fig. 7 and 8 are details in plan showing the os-
cillating wire guide in its two positions of move-
ment; and

40 Fig. 9 is a cross sectional elevation taken on
line 9—9 of Fig. 2 showing the wire feeding mech-
anism.

The machine as a whole is mounted upon a
45 rectangular base comprising a front wall 10, a
rear wall, 11, and end walls 12 and 13.

The base at the entering end for the wire pro-
vides support for a grooved guide roller 14, be-
neath which the wire W is fed and thence passes
50 between a group of wire straightening rolls 15
and between upper and lower feed rolls 16 and
17, which are driven at the desired feeding speed
by means presently to be described.

The wire fed forwardly by the bite of the feed
55 rolls passes through a second straightener 18 of

well known type, in the form of a rapidly driven
tube provided with sets of inwardly projecting
fingers 19 which are slightly staggered at their
inner wire contacting ends, so that as the
straightener is rapidly rotated all slight bends or
kinks in the wire will be eliminated. Mechanism
of this character is commonly employed in the art
for straightening purposes, so that further de-
tailed description is deemed unnecessary. The
leading end of the wire thus straightened passes
10 through an oscillating tubular wire guide 20
which, in conjunction with the rotary cutter rolls
21 and 22 having coacting cutter blades 23, con-
stitutes the essential feature of the present in-
vention. The axes of the cutter rolls extend 15
transversely of the line of travel of the wire, and
the surfaces of the rolls adjacent the cutter
blades are spaced to permit the free travel of the
wire between the roll surfaces which rotate in
unison in the direction of travel of the wire. 20

Referring to Fig. 4, the wire guide 20 is in the
form of a longitudinally extending tube through
which the wire freely passes. The wire guide,
near its rear end, is entered through the head 24
of a vertical rocking stem 25 journalled through
25 a bracket 26 located slightly to the rear of the
rotary cutters 21 and 22. The rocking stem 25
at its lower end has mounted thereon a collar 27
which receives the lower end of a coil spring 28,
the upper end of which is socketed within the 30
journal bracket 26, so that normally the oscil-
lating wire guide will be held in the position
shown in Fig. 7, which permits the wire to travel
forwardly and to the rear of the cutter blades 23
carried by the rotary cutter rolls. At recurrent 35
intervals, however, the guide will be swung into
the position shown in Fig. 8, which brings the
wire into the path of the cutter blades, so that at
the proper instant a section of wire will be sev-
ered and delivered into a trough or receptacle 29
located at the delivery end of the machine. 40

The wire guide 20 is oscillated at suitably
timed intervals by the mechanism best shown
in Fig. 3. This mechanism includes a thrust bar
30 which is slidably mounted within a guide 31
carried by the front wall of a boxlike housing 32
supported upon the base frame of the machine.
Within the housing is located a cam shaft 33
which mounts a cam 34 provided with a high
spot 35 so disposed that with each rotation of 45
the cam the bar 30 will be momentarily thrust
outwardly, thereby swinging the oscillating wire
guide to bring the wire in position to be severed
by the cutters. The cam shaft is mounted
within journals 36 and 37, and at its outer end 50

55

- carries a spur pinion 38 meshing with an idler 39 mounted upon a stub shaft 40 carried by a segmental plate 41 pivoted upon a jack shaft 42 carrying a driving pinion 43 in train with a pinion 44 on the stub shaft 40 which also carries the idler 39. The segmental plate 41 is provided with an arcuate slot 45 through which is entered a bolt 46 carrying a nut 47, which permits an adjustment of the segment with the pinions carried thereby, so that by employing a pinion 38 of the desired size, and adjusting the position of the stub shaft 40, variations in speed ratio can be made with a resultant variation in the timing of the oscillating wire guide.
- 15 The jack shaft 42 at its inner end mounts a bevel pinion 48, which meshes with a bevel pinion 49 carried by the cutter shaft 50 which at its forward end carries the lower cutter roll 22, thus establishing the desired speed ratio between the rotation of the cutter rolls and the oscillating periods of the wire guide. The cutter shaft 50 carries a spur pinion 51 meshing with a spur pinion 52 on a jack shaft 53 which carries the upper cutter 21. The jack shaft 53 is mounted within a journal bracket 54 slidably mounted within the front wall of the housing and adapted to be vertically adjusted by means of a screw 55 entered through the top wall of the housing, which arrangement permits limited adjustment of the spacing between the cutter rolls and the cutter blades carried thereby.
- 20 The cutter shaft 50 is carried by obliquely disposed roller bearings 56 and 57, and the jack shaft 53 by obliquely disposed roller bearings 58 and 59. The cam shaft 33 is so mounted that it extends longitudinally of the machine and between the shafts 50 and 53, as shown in Fig. 6. The cutter shaft 50 at its rear end is connected by a coupling 60 with a reducing train of any suitable form for establishing the desired speed ratio between the rotation of the feed rolls 16 and 17 and the cutter shafts and parts in train therewith. As shown for purposes of illustration only, the coupling 60 unites the cutter shaft 50 with a shaft section 61 carrying a pair of opposed beveled pulleys 62 adapted to be moved toward and from one another by the adjusting arms 63 carried by a right and left threaded adjusting screw 64.
- 25 The beveled pulleys 62, which constitute the driving elements, cooperate with beveled driven pulleys 65 adjustable by arms 66 mounted upon a right and left adjusting screw 67 having its threads in opposed relation to the threads of the adjusting screw member 64. The screw members are moved in unison by a sprocket connection 68, and the screw member 64 is manually adjusted from the front of the machine by means of a hand wheel 69 on the forward end of a shaft 70 connected through a sprocket chain 71 with the adjusting screw member 67, so that, by adjusting the latter, the pairs of beveled pulley members 65 and 62 will be simultaneously adjusted in reverse relation to one another to vary the speed ratio between the shaft 61 and a shaft 72, the beveled pulley members being connected by a belt 73.
- 30 The shaft 72 drives a sprocket-connection 74 which imparts rotation to the lower wire feed roller 17 which is mounted upon the forward end of a shaft 75 journalled by roller bearings 76 within a housing 77. The upper feed roller 16 is mounted upon the forward end of a jack shaft 78 journalled by roller bearings 79 carried by a slide bracket 80 mounted within the

housing and adapted to be vertically adjusted by the operation of a screw 81 carrying a hand wheel 82. This permits the feed rollers to be separated slightly to afford easy introduction of the wire or vary the spacing as occasion may require.

The detailed construction of the cutter rolls 21 and 22 is best illustrated in Figs. 4 and 6. Each of the cutters is in the form of a disk having a hub 83 and cooperating with a ring 84 having in its inner face one or more grooves 85 (Fig. 5), which socket the chisel shaped cutter blades 23, the parts being held together by dowels 86 and cap screws 87, and the inner end of each cutter blade bearing against the hub 83 of the cutter. This gives to the assembly the form of a cylindrical roll having projecting from its middle surface one or more chisel shaped cutter blades adapted to coact with a similarly mounted blade or blades on the companion roll.

20

Operation

In operation, the wire is fed continuously from a spool or other source, and is threaded through the wire straighteners and between the feed rolls 25 in the usual manner, until the leading end of the wire is inserted through the oscillating wire guide which normally holds the wire between the cutter disks but behind the paths of the cutter blades. The machine is then adjusted to accurately time the oscillations of the wire guide with respect to the feeding speed of the wire, and a proper gear ratio is employed in the driving train for the cutters so that the coating blades will arrive at the cutting point at the instant the desired length of wire has been fed forwardly.

30

The cutters rotate toward one another in the direction of advance of the wire, so that, even though the wire be traveling at a rapid rate of speed, a clean cut will be effected without pause in the advancement of the wire, and the severed sections will be thrown forwardly and accumulated in the bin or receptacle provided therefor. If, therefore, it is desired to uniformly cut sections of two feet in length for example, the machine will be adjusted to feed this amount of wire forwardly in accurately timed relation to the arrival of the cutter blades at the point of severance, and the oscillating wire guide will also be timed to this ratio, so that by establishing proper timing between these three instrumentalities, accuracy in the cutting off of the wire sections will be insured.

40

The machine as a whole is of simple and rugged construction, and by operating the machine continuously rather than intermittently the speed of operation can be materially increased and wear and tear on the operating parts reduced to a minimum.

50

Although the invention has been described with particularity as to details, it is obvious that numerous changes in the construction may be introduced without departing from the spirit of the invention. Furthermore, although the machine is defined as a wire cutter, it is intended by the term wire to cover and include strips or lengths of material of similar or analogous character which by flexion can be brought into the path of the cutters in the manner described.

60

I claim:

1. In a machine of the class described, the combination of wire feeding rolls adapted to feed the wire forwardly, a wire guide normally extending in the straight line of advance of the wire delivered from the feeding rolls and through

70

75

which the wire is fed, said wire guide being adapted to have its discharge end moved laterally, means for recurrently actuating the wire guide, a pair of spaced rotating cutter rolls presenting unobstructed surfaces for the passage of the wire between them when the guide is standing in normal position and rotating in the direction of movement of the wire and each carrying an outwardly projected cutter blade positioned to rotate in a path laterally adjacent to the normal path of movement, said cutter blades adapted in conjunction to sever lengths of wire when the discharge end of the wire guide is moved laterally to bring the wire into the path of the cutter blades, and driving connections between the wire feeding rolls, the means for actuating the wire guide, and the cutters, for actuating the parts in timed relation to one another.

2. In a machine of the class described, the combination of wire feeding rolls adapted to feed the wire forwardly, a wire guide normally extending in the straight line of advance of the wire delivered from the feeding rolls and through which the wire is fed, an oscillating mounting for the rear end of the wire guide in the form of a spring backed vertically disposed post having its axis at substantially right angles to the line of travel of the wire and adapted to permit the wire guide to be moved laterally, means including a cam and connections for recurrently oscillating the wire guide, a pair of spaced rotating cutter rolls presenting an unobstructed surface for the passage of the wire between them when the guide is standing in normal position and each carrying a cutter blade positioned to rotate in a path laterally adjacent to the normal path of movement of the wire and adapted in conjunction to sever lengths of wire when the wire guide is moved laterally to bring the wire into the path of the cutter blades, and driving connections between the wire feeding rolls, the means for oscillating the wire guide, and the cutters, for actuating the parts in timed relation to one another.

3. In a machine of the class described, the combination of wire feeding rolls adapted to feed the wire forwardly, a wire guide normally extending in the straight line of advance of the wire delivered from the feeding rolls and through which the wire is fed, an oscillating mounting for the rear end of the wire guide adapted to permit the wire guide to be moved laterally, means for recurrently oscillating the wire guide, a pair of spaced rotating cutter rolls presenting an unobstructed surface for the passage of the wire between them when the guide is standing in normal position and each carrying a cutter blade having a chisel edge standing transversely to the line of advance of the wire and positioned to rotate in a path laterally adjacent to the normal path of movement of the wire and adapted in conjunction to sever lengths of wire when the wire guide is moved laterally to bring the wire into the path of the cutter blades, and driving connections between the wire feeding rolls, the means for oscillating the wire guide, and the cutters, for actuating the parts in timed relation to one another.

4. In a machine of the class described, the combination of wire feeding rolls adapted to feed the wire forwardly, a wire guide normally extending in the straight line of advance of the wire delivered from the feeding rolls and through which the wire is fed, an oscillating mounting for the rear end of the wire guide in the form of a spring backed vertically disposed post having its axis at substantially right angles to the line of

travel of the wire and adapted to permit the wire guide to be moved laterally, means including a cam and connections for recurrently oscillating the wire guide, a pair of spaced rotating cutter rolls presenting an unobstructed surface for the passage of the wire between them when the guide is standing in normal position and each carrying a cutter blade having a chisel edge standing transversely to the line of advance of the wire and positioned to rotate in a path laterally adjacent to the normal path of movement of the wire and adapted in conjunction to sever lengths of wire when the wire guide is moved laterally to bring the wire into the path of the cutter blades, and driving connections between the wire feeding rolls, the means for oscillating the wire guide, and the cutters, for actuating the parts in timed relation to one another.

5. In a machine of the class described, the combination of wire feeding rolls adapted to feed the wire forwardly, a wire guide normally extending in the straight line of advance of the wire delivered from the feeding rolls and through which the wire is fed, an oscillating mounting for the rear end of the wire guide adapted to permit the wire guide to be moved laterally, means for recurrently oscillating the wire guide, a pair of spaced rotating cutter rolls presenting an unobstructed surface for the passage of the wire between them when the guide is standing in normal position and each carrying a cutter blade having a chisel edge standing transversely to the line of advance of the wire and positioned to rotate in a path laterally adjacent to the normal path of movement of the wire and adapted in conjunction to sever lengths of wire when the wire guide is moved laterally to bring the wire into the path of the cutter blades, and driving connections between the wire feeding rolls, the means for oscillating the wire guide, and the cutters, for actuating the parts in timed relation to one another, and continuously rotating the cutter blades in unison in the direction of travel of the wire.

6. In a machine of the class described, the combination of wire feeding rolls adapted to feed the wire forwardly, a wire guide normally extending in the straight line of advance of the wire delivered from the feeding rolls and through which the wire is fed, an oscillating mounting for the rear end of the wire guide in the form of a spring backed vertically disposed post having its axis at substantially right angles to the line of travel of the wire and adapted to permit the wire guide to be moved laterally, means including a cam and connections for recurrently oscillating the wire guide, a pair of spaced rotating cutter rolls presenting an unobstructed surface for the passage of the wire between them when the guide is standing in normal position and each carrying a cutter blade having a chisel edge standing transversely to the line of advance of the wire and positioned to rotate in a path laterally adjacent to the normal path of movement of the wire and adapted in conjunction to sever lengths of wire when the wire guide is moved laterally to bring the wire into the path of the cutter blades, and driving connections between the wire feeding rolls, the means for oscillating the wire guide, and the cutters, for actuating the parts in timed relation to one another, and continuously rotating the cutter blades in unison in the direction of travel of the wire.

7. In a machine of the class described, the combination of wire feeding rolls adapted to feed the wire forwardly, a wire guide normally extending

in the straight line of advance of the wire delivered from the feeding rolls and through which the wire is fed, said wire guide adapted to have its forward end moved laterally, means for recurrently moving the forward end of the wire guide laterally, a pair of spaced rotating cutter rolls presenting an unobstructed surface for the passage of the wire between them when the guide is standing in normal position and each carrying a cutter blade having a chisel edge standing transversely to the line of advance of the wire and positioned to rotate in a path laterally ad-

5 jacent to the normal path of movement of the wire and adapted in conjunction to sever lengths of wire when the wire guide is moved laterally to bring the wire into the path of the cutter blades, and driving connections between the wire feeding rolls, the means for moving the wire guide, and the cutters, for actuating the parts in timed relation to one another, and continuously rotating the cutter blades in unison in the direction of travel of the wire.
